UNITED STATES PATENT OFFICE.

JAMES COCHRANE HUTTON, OF BIRMINGHAM, ENGLAND, ASSIGNOR TO THE BRITISH LIGHTING AND IGNITION COMPANY, LIMITED, OF BIRMINGHAM, ENGLAND, A BRITISH COMPANY.

DYNAMO-ELECTRIC MACHINE.

Application filed May 19, 1925, Serial No. 31,319, and in Great Britain May 16, 1924.

This invention relates to dynamo-electric machines of the type consisting of a combined unit comprising an ignition magneto of the kind in which the armature is fixed and there is employed in conjunction therewith a rotary unwound permanent magnet or rotary unwound inductors and stationary unwound permanent magnets and an electric dynamo supplying continuous current, the latter also serving if desired as a starter motor.

In the usual arrangements of apparatus of this type where the ignition magneto and the dynamo have been provided with a common drive and thus positioned axially in relation to one another, it has been necessary to provide a coupling member between the respective driving shafts of the magneto and the dynamo and to support each of the driving shafts in two bearings, thus involving the use of four bearings in all. With such an arrangement the length of the combined unit is very considerable owing to the number of bearings employed and the space occupied by the coupling member. With the object of shortening the total length of a combined unit as above referred to it has been proposed to employ only two bearings for the driving shaft of the dynamo and to attach the rotor of the magneto to an extension of the dynamo shaft; in this arrangement however the rotor was carried by a portion of the driving shaft external to or beyond the bearings, but was otherwise unsupported.

The present invention has for its object to enable two bearings only for the common driving shaft of the combined magneto and dynamo to be employed while at the same time enabling the rotating portion of the magneto to be supported near both ends of its axis of rotation.

As a matter of convenience the common driving or through shaft of the combined magneto and dynamo, instead of being constructed as a single shaft, may be made in two portions with a rigid coupling between the magneto and dynamo armature portions, and it is to be understood that the expression "common driving shaft" as employed throughout this specification and claims is used as denoting a shaft comprising either a single member or two members rigidly coupled together.

A combined unit of the kind referred to according to the present invention comprises an ignition magneto and a dynamo, or magneto and a combined dynamo and starter, in which there is provided a common driving shaft for the rotor of the magneto and the armature of the dynamo, said shaft being supported near its extreme ends by two bearings only between which bearings the rotor of the magneto is located. This construction, allows of the dynamo and magnet being mounted together in the same casing. The shaft on which the dynamo and magneto are mounted may be arranged vertically or horizontally as desired.

In order that the said invention may be clearly understood and readily carried into effect, the same will now be described more fully with reference to the accompanying diagrammatic drawings in which:—

Figure 1 represents an arrangement with a magneto and dynamo mounted together in the same casing.

Figure 2 represents an arrangement similar to that shown in Figure 1 but with the contact breaker and distributor gears arranged outside the adjacent bearing.

Figure 3 represents a further arrangement provided with means for controlling the timing of the magneto.

Figure 4 represents an arrangement with a magneto provided with a further means for controlling the timing of the magneto and a dynamo mounted together in the same casing.

Referring to the arrangements illustrated in Figures 1 2 and 3 of the drawings, there is provided for the dynamo armature 1 and the rotor of the magneto, of which 2 is the rotatable magnet and 3 the stationary armature, a common driving shaft 14 which is supported in the two bearings 7; 8 represents the casing and field magnet system of the dynamo and 9 the cover for the magneto. The high tension distributor 4 of the magneto is driven through reduction gearing 5, which may be of any usual type such as spur, skew, worm, or bevel gearing. As shown in Figure 1 the gearing 5 and the contact breaker or cam 6 are mounted on a portion of the common driving shaft between the two bearings 7, whilst in the arrangement shown in Figure 2 they are mounted on an extension

15 of the shaft outside, namely to the left of, the adjacent bearing 7.

In the modification shown in Figure 3, which is adapted to allow of hand operated control of the timing of the spark, the rotating magnet system, or inductors of the magneto, the gear drive 5 to the high tension distributor 4 and the contact breaker or cam 6 are mounted on the sleeve 11, which 10 sleeve is rotatably mounted on the driving shaft 14 and can be given an angular movement dependent upon the speed of the said driving shaft, so that angular displacement may be obtained between the sleeve and the 15 shaft. The disclosure of Fig. 4 shows the combination of a dynamo and an ignition magneto, as generally shown in Figs. 1 and 20 3, with a means for manually adjusting the timing of the spark. In addition to the dynamo 1 on the common driving shaft, the driving shaft 14 is made up of a hollow portion 14' adapted to receive a solid portion 19, which is movable longitudinally from the outside of the machine. The portion 25 19 carries a pin 20 which slides along a slot 21 in the portion 14', and also engages with an elongated slot 22 in the rotatable hub 11 which carries the distributor gears 5 and the contact breaker or cam 6. This 30 arrangement allows the adjustment of the timing of the spark by moving the part 19 into or out of the hollow portion of the shaft 14'.

What I claim and desire to secure by Letters Patent of the United States is:—

1. A combined unit of the kind referred

to comprising an ignition magneto provided with a fixed armature and a rotor and an electric dynamo provided with a rotary armature, a common driving shaft for the 40 rotor of the magneto and the armature of the dynamo, two bearings only, between which said rotor of the magneto is located, for supporting said common driving shaft near its extreme ends, a sleeve on which the 45 rotor is rotatably mounted on said common driving shaft, a high tension distributor driven from said sleeve, a contact breaker, said contact breaker being actuated by said sleeve, and means for effecting relative angular displacement between the sleeve and the 50 shaft for controlling the timing of the spark.

2. A combined unit of the kind referred to as in claim 1, in which said driving shaft 55 is made hollow at one end and there is provided a solid shaft carrying a pin, said solid shaft being longitudinally movable within the hollow part of the driving shaft, said hollow part of the driving shaft being 60 provided with an elongated slot cut at an angle to the axis and said sleeve being provided with an elongated slot cut at an angle to the axis opposite to that of the slot formed in the driving shaft, and said pin 65 carried by the solid shaft engaging with the slots in the driving shaft and sleeve so that axial movement of the solid shaft and the pin carried thereby imparts angular movement to the sleeve.

JAMES COCHRANE HUTTON.
